SELF ALIGNING PUMP ADJUSTER

Filed April 17, 1928

UNITED STATES PATENT OFFICE

WILLARD L. BOROUGH, OF LOS ANGELES, CALIFORNIA

SELF ALIGNING PUMP ADJUSTER

Application filed April 17, 1928. Serial No. 270,729.

My invention relates to the oil-well industry, and comprises a new and novel self-aligning pump-adjusting mechanism.

In the oil-well industry it is customary to install a pump barrel in the well, usually below the surface of the oil therein. A plunger is adapted to move in this pump barrel, this plunger being reciprocated by a string of sucker rods extending to the surface of the ground. A polish-rod is secured to the upper end of the string of sucker rods, this polish-rod extending through a packing gland and being connected to a walking-beam so as to be reciprocated thereby.

The usual form of connection includes a saddle connected to the polish-rod and pivoted to one outer end of the walking-beam. Due to the fact that the path of this outer end is arcuate in form, it is impossible to pull directly upward on the polish-rod throughout the length of the stroke. The result is that with every pumping stroke, the polish-rod is successively bent and strained, thus, in time causing this rod to break due to a fatigue failure. Such a failure is ordinarily spoken of as being caused by "crystallization". This swing action of the upper end of the polish-rod also causes undue wear on the stuffing-box.

It is an object of my invention to provide an improved mechanism for connecting a walking-beam to a polish-rod.

In accomplishing this object, I provide a connecting means in the form of reins, these reins being in pivotal relation with the walking-beam and with a clamp holding the polish-rod so as to be movable in a plane which is substantially the same as the plane of movement of the walking-beam.

It is an object of my invention to provide a device for operatively connecting a walking-beam and a clamp, this device being pivoted to both the beam and the clamp so as to be movable in a plane substantially the same as the plane of movement of the walking-beam.

I accomplish this pivotal connection between the reins and the walking-beam by means of a supporting member supported in universal-joint relationship with the walk-

ing-beam so as to be self-aligning with the polish-rod.

It is an object of my invention to provide a self-aligning pumping mechanism in which a supporting member is held in universal-joint relationship with regard to the walking-beam.

Another object of my invention is to provide an adjustable brace for determining the position of this supporting member.

Still other objects of my invention will be made evident hereinafter, these objects being realized in the novel construction of my apparatus.

My invention may best be understood by referring to the drawings, in which—

Fig. 1 is a side view of my device as applied to a walking-beam.

Fig. 2 is an end view taken in the direction of the arrow 2 of Fig. 1.

Fig. 3 is a sectional view taken on the line 3—3 of Fig. 1.

Fig. 4 is a sectional view taken on the line 4—4 of Fig. 2.

Fig. 5 is a sectional view taken on the line 5—5 of Fig. 2.

Referring particularly to Figs. 1 and 2, I illustrate a Samson post 10 which supports a bearing 11 at its upper end. Journalled in this bearing is a shaft 12 which is suitably secured to a walking-beam 13. This walking-beam is adapted to be oscillated by a mechanism, not shown. The movement of this walking-beam is transferred to a polish-

rod 15 by a connecting means 18 incorporating the features of my invention. The connecting means 18 is secured to an outer end 19 of the walking-beam 13. Inasmuch as this outer end moves through an arcuate path as

the walking-beam 13 is oscillated, it has heretofore been impossible to reciprocate the polish-rod 15 through a true vertical path. Thus, a reversal of stress takes place in the outer fibers of the polish-rod every time this rod is reciprocated. Such a reversal of stress ultimately causes a fatigue failure of the polish-rod.

The polish-rod 15 is adapted to slide in fluid-tight relationship with a packing gland 20, and this non-vertical movement of the polish-rod causes undue wear on this

packing gland. The connecting means 18 of my invention is designed to eliminate these difficulties.

This connecting means comprises a supporting member 22 which extends through an opening 23 formed in the outer end 19 of the walking-beam. This supporting member is secured to the walking-beam by a means best indicated in Figs. 1 and 3, this means comprising a pair of blocks 25 suitably secured to the upper surface of the walking-beam. These blocks have openings 26 therein which are adapted to hold a shaft 27 in position. This shaft 27 has a ball portion 28 spaced centrally between the blocks 25 and in alignment with the opening 23. The supporting member 22 has a hub 29 through which an opening 30 is formed. In the upper end of the opening 30 is formed a socket 31 which is adapted to bear against the ball portion 28. The socket 31 is so formed as to be in surface contact with the ball portion 28 so that the supporting member 22 is supported in universal-joint relationship with the walking-beam 13.

This supporting member 22 is normally kept from pivoting about the ball portion 28 in the plane of movement of the walking-beam by means of an adjustable brace 33, this brace extending between an upper arm 34 of the supporting member 22 and a member 35 secured to the upper face of the walking-beam. The brace is pivoted to the arm 34 and the member 35, and has a turnbuckle 36 therein to permit an adjustment of its length. This adjustable brace is important to my invention as is also the placement of the blocks 25 and the member 35 on top of the walking-beam. These members may be installed and correctly positioned by one man sitting on the walking-beam, the supporting member and its attached parts being supported from the derrick by an eye 37 at the top of the arm 34.

The lower end of the supporting member 45 comprises a lower arm 40 having a retaining member 41 formed at the lower end thereof. This retaining member is preferably cup-shaped, the lower portion of this cup having a channel 42 therein, as best indicated in Fig. 4. The retaining member 41 has side walls 43 so that it may hold a body of oil. Adapted to pivot in the retaining member 41 is an engager 45 which rests in surface contact with the channel 42. This engager is substantially the same length as the interior of the retaining member so that there will be no excessive end-play between the engager and the retaining cup member. The engager and the channel 42 are continually lubricated by the body of oil in this retaining member. This engager also has outward extending arms 47 which are drilled to receive reins 48, these reins being supported from the arms 47 through nuts 49 threaded to the reins and engaging the upper surface of these arms.

The lower end of the reins 48 have eyes 50 thereon, these eyes being adapted to be pivotally supported by a clamp 53 which, in turn, adjustably clamps the polish-rod 15. The details of the clamp 53 may best be understood by reference to Fig. 5. The clamp 53 comprises a body 55 having trunnions 56 extending outward therefrom. These trunnions are formed to receive the eyes 50 of the reins 48, the eyes being held in position by means of U members 58 which engage a reduced diameter portion 59 of each trunnion 56. A cotter-pin 60 is passed through the lower end of these U members to retain them in position. The body 55 has an engaging surface 62 which is of the same contour as the external surface of the polish-rod 15. The polish-rod engages this surface and is clamped thereagainst by means of a follower 64 actuated by a screw 65. This screw is threaded through one of the trunnions 56 and has a suitable tightening means 67 secured thereto. This tightening means may be in the form of a hand wheel or is preferably formed with a T-head. By operating the tightening means 67, the polish-rod is tightly clamped in the clamp 53 so that the oscillations of the walking-beam will be transferred to the polish-rod through the supporting structure 22 and the reins 48, these reins being utilized as a connecting means between the supporting member and the polish-rod.

The channel 42 of the retaining member 41 is formed parallel to the trunnions 56 and also substantially perpendicular to the point of movement of the walking-beam. Thus, the reins 48 may be pivoted relative to the clamp 53 and the retaining member 41 so as to move in a plane which is substantially parallel to the plane of movement of the walking-beam.

In setting up the mechanism of my invention, the walking-beam should be lowered into its lowermost operating position, as indicated in full lines in Fig. 1. The blocks 25 should then be installed so that the supporting member 22 lies substantially in the center of the opening 23. The adjustable brace 33 is next installed and the member 35 secured in place after which the turnbuckle 36 should be adjusted to make the supporting member 22 lie substantially vertically when the walking-beam is in its lowermost position. This lowermost position of the walking-beam should be such that the movement of the channel 42 of the retaining member 41 will be equally spaced above and below the horizontal center line of the bearing 11. Thus, when in its uppermost position, the mechanism will be in a position indicated by dotted lines 75 of Fig. 1. During this upward movement the channel 42 will swing through an arc and the upper ends of the reins 48 will be moved to the right, a maximum movement taking place when the channel 42 lies on the horizontal center line of the bearing 12. Due,

however, to the journalling action between the reins 48 and the retaining member and clamp, the polish-rod 15 will not be unduly bent but may be reciprocated on a substantially vertical axis thus reducing the wear on the packing gland 20 and also decreasing or entirely eliminating the bending stresses on the polish-rod.

The relationship between the supporting member and the walking-beam constitutes a very important part of my invention. Ordinarily, it is necessary to very accurately align the shaft 27, or an equivalent shaft journaling the conventional saddle so often used, with the shaft 12 journalled in the Samson post bearings. If this is not done there will be undue wear on the shaft 27 and the sucker rods will be placed under an additional bending stress. My novel type of universal-joint connection between the supporting member and the walking-beam allows the supporting member to be self-aligned relative to the polish-rod. Furthermore, the adjustable brace 33 offers a very convenient means of adjusting the position of the supporting member and holding it firmly in place.

I claim as my invention:

1. In combination: a walking-beam; a supporting member carried in universal-joint relationship with said walking-beam; a cup member carried by said supporting member; an engager pivotally resting in said cup member; a clamp; a polish-rod secured in said clamp; and reins connecting said engager and said clamp.

2. In combination: a walking-beam; blocks mounted on the upper end of said walking-beam; a shaft mounted in said blocks, said shaft having a ball portion thereon; a supporting member; a socket on said supporting member, said socket engaging said ball portion; a cup member carried by said supporting member; an engager pivotally resting in said cup member; a clamp; a polish-rod secured in said clamp; and means connecting said engager and said clamp.

3. In combination: a walking-beam; blocks mounted on the upper end of said walking-beam; a shaft mounted in said blocks, said shaft having a ball portion thereon; a supporting member; a socket on said supporting member, said socket engaging said ball portion; an adjustable brace extending between said supporting member and the upper side of said walking-beam; a cup member carried by said supporting member; an engager pivotally resting in said cup member; a clamp; a polish-rod secured in said clamp; and means connecting said engager and said clamp.

In testimony whereof, I have hereunto set my hand at Los Angeles, California, this 11th day of April, 1928.

WILLARD L. BOROUGH.
